CLAMPING DEVICE

Fred W. Kuppersmith, Bloomington, Ill.

Application February 15, 1946, Serial No. 647,926

8 Claims. (Cl. 192—8)

1

My invention relates to clamping devices.

One of the objects of my invention is to provide an improved clamping device having a relatively quick take-up movement and means for holding the clamping jaws in clamping position when substantial resistance to movement of the movable jaw is encountered.

Further objects and advantages of the invention will be apparent from the description and claims.

In the drawings, in which several embodiments of my invention are shown,

Figure 1 is a plan view of a tool jig fixture embodying my improved clamping device;

Fig. 2 is an elevational view of Fig. 1;

Fig. 3 is a sectional view of the lower part of the fixture, substantially on the line 3—3 of Fig. 1, and is also substantially a cross-sectional view on the line 3—3 of Figs. 8 and 10;

Fig. 4 is a sectional view on the line 4—4 of Fig. 3;

Fig. 5 is a sectional view on the line 5—5 of Fig. 3;

Fig. 6 is a sectional view on the line 6—6 of Fig. 3;

Fig. 7 is a sectional view on the line 7—7 of Fig. 3;

Fig. 8 is an elevational view of a vise embodying my invention;

Fig. 9 is a section on the line 9—9 of Fig. 8, and

Fig. 10 is an elevational view showing another form of vise embodying my invention.

Referring to the drawings in detail, and first to Figs. 1—7, incl., the construction shown therein comprises a tool jig fixture having a base portion 1 provided with a face plate portion 2 which also serves as a clamping element, a jig plate element or jaw 3, to which leader pins 4 are secured slidably mounted in sleeves 5 extending upwardly from the base portion, a crankshaft 6 rotatably mounted in suitable bearings in the base plate, and a pair of pinions 8 formed on this shaft and meshing with rack teeth 9 on the leader pins. The upper clamping jig plate 3 may be provided with suitably positioned bushings 10 for positioning and guiding the drills.

When a piece of work is placed in the fixture, it is clamped in place by rotating the crankshaft 6 by means of the operating handle or crank 11 to cause the leader pins 4 to move downwardly and draw the upper plate 3 down against the work. The construction is such that, when the upper plate 3 engages the work, thus arresting the downward movement of the leader pins 4 and

the rotation of the pinions 8, further motion of the crank which is swiveled on the crankshaft 6, will effect a clamping action which will bind the crankshaft against rotation, thus preventing the face plate 3 from releasing the work when the pressure on the crank is released. The construction provided for this purpose, shown in detail in Fig. 3, comprises in addition the shaft 6, pinions 8 and racks 9, a first friction face element 12 rotatable with the shaft and held against axial movement thereon by the pin 13, a second friction face element 14 held against rotation and axial movement and formed as an integral boss on the base 1 and engageable with said first friction face element 12 for holding the shaft 6 against rotation, a third friction face element 15 rotatable with the shaft and axially movable thereon, a fourth friction face element 16 held against rotation and axial movement and formed as an integral boss on the base and engageable with said third friction face element 15 for holding the shaft against rotation, compression spring means 17 tending to separate said engageable friction face elements, and means for forcing the engageable friction face elements into engagement when the upper face plate or clamping jaw engages the work to prevent further movement of the leader pin racks 9 and of the shaft 6 carrying the pinions 8 which engage these racks.

20 The means for causing frictional engagement of the frictional face elements comprises a face plate cam construction including three hardened balls 18 rotatable in pockets 19 in the friction face element 15 and engaging arcuate recesses 20 in the face of the hub 21 of the crank arm or lever 11 which has a limited swiveling motion on the shaft. This hub 21 is held against axial movement on the shaft by means of anti-friction balls 22 bearing in the opposing raceways on the hub 21 and on the nut 23 which is screwed tightly into the end of the shaft 6.

25 The arcuate recesses 20 in the face of the hub 21 are tapering in depth, being deepest in the middle portion and tapering gradually toward the ends. With this construction movement of the hub 21 relative to the friction face element 15 from the medial position of the arcuate recesses 20 with respect to the balls will cause the face of the hub to separate further from the opposing face of the friction face element. This will force the friction face on the element 12 into engagement with the friction face on the element 14 and will force the friction face of the element 15 into engagement with the friction face of the element 16.

In order to hold the hub 21 so that the medial portion of the recesses 20 will normally engage the balls, the coil compression spring 17 is provided, seated in an axial recess 24 in the shaft 6 and bearing at one end on a hardened ball 25 seated at the bottom of the recess and at its other end on a shoulder 26 on a screw 27 threaded in a nut 28 axially slidable in the recess 24 and keyed or splined to the shaft 6. The nut 28 is provided with a central opening 29 affording access to the head of this screw for adjusting the tension of the spring.

For holding the friction element 15 and the nut 28 against rotation with respect to the shaft 6 and still enabling relative axial movement of the nut and friction element, the nut and friction element are provided with milled keyways 30 and 31 and the tubular portion of the shaft is provided with slots 32 registering with these keyways, in which registering keyways and slots are seated the hardened circular disc keys 33. These disc keys 33 are engageable with the arcuate end of the milled keyways 30 and 31 to prevent relative axial movement of the nut 28 and friction element 15 beyond a certain distance in one direction.

In use, in clamping the work in the fixture, the initial take-up movement of the upper jaw is effected by the rotation of the crankshaft 6, causing the pinions 8 acting on the racks 9 to pull the leader pins 4 carrying the upper jaw 3 downwardly until it engages and clamps the work. When the upper jaw engages and clamps the work the shaft is prevented from further rotation. The tension of the coil compression spring 17 is sufficient during this initial movement to press the hub 21 of the lever and the friction element 15, which is splined to the shaft 6, toward each other to hold the medial portion of the recesses 20 in engagement with the balls 18, thus preventing any substantial relative rotation of the hub 21 and friction element 15 and avoiding any substantial frictional engagement between the friction faces of the friction elements. When the engagement of the upper jaw 3 with the work stops further rotation of the shaft 6, the machinist may continue to press the lever to effect a limited additional movement thereof, causing the hub 21 to rotate with respect to the friction element 15 to bring the shallower portions of the arcuate recesses 20 into engagement with the balls 18 and to further separate the hub 21 and friction element 15. In this separating movement, the nut 28 may slide in the axial recess 24 in the shaft 6 to enable the separating movement, this sliding movement of the nut being necessary because of the engagement of the circular disc keys 33 with the arcuate ends of the milled keyways.

As the hub 21 separates further from the friction element 15, the hub will exert endwise thrust on the ball race member 23 which is threaded into the operating shaft 6. This end thrust acting on the shaft 6 will cause the friction face element 12 to be drawn snugly against the friction face element 14 and the cam pressure on the balls will cause the friction face element 15 to be pressed snugly against the friction face element 16. This will effectually lock the shaft against rotation when pressure on the operating lever is removed.

To release the clamping jaws the lever 11 is rotated in the direction opposite to the clamping movement. This brings the medial portions of the arcuate recesses 20 again into engage-

ment with the balls 18 allowing the friction faces to disengage whereupon, due to the action of the spring 17, further rotation of the operating lever will cause rotation of the operating shaft 6 and upward movement of the leader pins 4, releasing the upper clamping jaw 3 from engagement with the work.

The construction shown in Figs. 8 and 9 is in many respects similar to that just described. Figs. 8 and 9, however, show my invention embodied in a vise. The construction shown comprises a base 34 having a fixed clamping jaw 35 and a movable clamping jaw 36 slidably mounted on the base 34 and operated in its sliding movement by means of a shaft 6 rotatably mounted on the movable jaw 36, having a pinion portion 8 engaging a rack 39 secured to the middle portion of the base. The sliding jaw 36 is mounted on parallel guides 40 at the sides of the base and held in position by means of gibbs 41 secured to the sliding jaw.

In operation, the work is placed on the table of the base and the crank is operated to rotate the shaft having the pinion portion engaging the rack. This effects a quick initial pick-up movement.

The construction shown in Fig. 10 is quite similar to that shown in Figs. 8 and 9. In this form, however, the sliding jaw is provided with an internally screw-threaded bore which is engaged by a threaded portion 43 of the operating shaft 6. The parts shown in cross section in Fig. 3 may be the same as the corresponding parts described in connection with Figs. 3 and 8. In use, rotation of the shaft effects a relative quick-closing movement of the jaw 42 with respect to the jaw 43. When the movable jaw 42 engages the work, further rotation of the shaft 6 is prevented and the final clamping action is effected by the lost-motion movement of the operating crank 11 with respect to the shaft 6.

As previously indicated, Fig. 3 is substantially a cross section of the construction on the section lines 3—3 of Figs. 1, 8 and 10. This construction has been described in connection with Fig. 1 and will now be described only in a general way in connection with Figs. 8 and 10. It comprises the handle 11, the friction face element 12 rotatable with the shaft 6, a second friction face element 14 engageable with the friction face element 12, a third friction face element 15 rotatable with the shaft, a fourth friction face element held against rotation, a compression spring 17 tending to separate the friction face elements, hardened balls 18 engaging the arcuate recesses 20, anti-friction balls 22, screw 27, nut 28 and keys 33.

When the engagement of the movable jaw (36 in Figs. 8 and 9 and 42 in Fig. 10) with the work stops further rotation of the shaft 6, the machinist may continue to press the lever 11 to effect a limited additional movement thereof, causing the hub 21 to rotate with respect to the friction element 15 to bring the shallower portions of the arcuate recesses 20 into engagement with the balls 18 and to further separate the hub 21 and friction element 15. In this separating movement, the nut 28 may slide in the axial recess 24 in the shaft 6 to enable the separating movement.

As the hub 21 separates further from the friction element 15, the hub will exert endwise thrust on the ball race member 23. This end thrust will cause the friction face elements 12 and 14 and the

friction face elements 15 and 16 to be drawn together to lock the shaft 6 against rotation.

To release the clamping jaws, the lever 11 is rotated in a direction opposite to the clamping movement. This will cause rotation of the operating shaft 6, releasing the clamping jaw 38 from engagement with the work.

Further modifications will be apparent to those skilled in the art and it is desired, therefore, that the invention be limited only by the scope of the appended claims.

Having thus described my invention, what I claim and desire to secure by Letters Patent is:

1. A clamping device comprising two relatively adjustable members and means for effecting relative adjustment of said members and holding them in adjusted position comprising a rotatable shaft for adjusting said members, a first friction face element rotatable with said shaft and held against axial movement thereon, a second friction face element held against rotation and axial movement and engageable with said first friction element for holding the shaft against rotation, a third friction face element rotatable with said shaft, nonrotatable with respect thereto and axially movable thereon, a fourth friction face element held against rotation and axial movement and engageable with said third friction face element for holding the shaft against rotation, spring means tending to separate said engageable friction face elements, and actuating means for rotating said shaft when the friction face elements are not engaged and forcing the engageable friction face elements into engagement when the shaft encounters increased resistance to rotation comprising an actuating element mounted on said shaft and having a limited rotation with respect thereto, and cam means acting when the shaft encounters resistance and the actuating means are rotating with respect to said shaft to force the engageable friction face elements into engagement.

2. A clamping device comprising two relatively adjustable members and means for effecting relative adjustment of said members and holding them in adjusted position comprising a rotatable shaft for adjusting said members, a first friction face element rotatable with said shaft and held against axial movement thereon, a second friction face element held against rotation and axial movement and engageable with said first friction element for holding the shaft against rotation, a third friction face element rotatable with said shaft, nonrotatable with respect thereto and axially movable thereon, a fourth friction face element held against rotation and axial movement and engageable with said third friction face element for holding the shaft against rotation, spring means tending to separate said engageable friction face elements, means for adjusting the tension of said spring means, and actuating means for rotating said shaft when the friction face elements are not engaged and forcing the engageable friction face elements into engagement when the shaft encounters increased resistance to rotation comprising an actuating element mounted on said shaft and having a limited rotation with respect thereto, and cam means acting when the shaft encounters resistance and the actuating means are rotating with respect to said shaft to force the engageable friction face elements into engagement.

3. A clamping device comprising two relatively adjustable members and means for effecting relative adjustment of said members and holding

them in adjusted position comprising a rotatable shaft for adjusting said members, a first friction face element rotatable with said shaft and held against axial movement thereon, a second friction face element held against rotation and axial movement and engageable with said first friction element for holding the shaft against rotation, a third friction face element rotatable with said shaft, nonrotatable with respect thereto and axially movable thereon, a fourth friction face element held against rotation and axial movement and engageable with said third friction face element for holding the shaft against rotation, spring means tending to separate said engageable friction face elements, and actuating means for rotating said shaft when the friction face elements are not engaged and forcing the engageable friction face elements into engagement when the shaft encounters increased resistance to rotation comprising an actuating element mounted on said shaft having a limited rotation with respect thereto and held against axial movement thereon, and cam means acting between said actuating element and one of said axially movable friction face elements when the shaft encounters resistance and the actuating means are rotating with respect to said shaft to force the engageable friction face elements into engagement.

4. A clamping device comprising two relatively adjustable members and means for effecting relative adjustment of said members and holding them in adjusted position comprising a rotatable shaft for adjusting said members, a first friction face element rotatable with said shaft and held against axial movement thereon, a second friction face element held against rotation and axial movement and engageable with said first friction element for holding the shaft against rotation, a third friction face element rotatable with said shaft, nonrotatable with respect thereto and axially movable thereon, a fourth friction face element held against rotation and axial movement and engageable with said third friction face element for holding the shaft against rotation, spring means tending to separate said engageable friction face elements, and actuating means for rotating said shaft when the friction face elements are not engaged and forcing the engageable friction face elements into engagement when the shaft encounters increased resistance to rotation comprising an actuating element mounted on said shaft having a limited rotation with respect thereto and held against axial movement thereon, and ball cam means acting between said actuating element and one of said axially movable friction face elements when the shaft encounters resistance and the actuating means are rotating with respect to said shaft to force the engageable friction face element into engagement.

5. A clamping device comprising two relatively adjustable members and means for effecting relative adjustment of said members and holding them in adjusted position comprising a rotatable shaft for adjusting said members, a first friction face element rotatable with said shaft and held against axial movement thereon, a second friction face element held against rotation and axial movement and engageable with said first friction element for holding the shaft against rotation, a third friction face element rotatable with said shaft, nonrotatable with respect thereto and axially movable thereon, a fourth friction face element held against rotation and axial movement and engageable with said third friction face element for holding the shaft against rotation,

helical spring means coaxial with said shaft tending to separate said engageable friction face elements, and actuating means for rotating said shaft when the friction face elements are not engaged and forcing the engageable friction face elements into engagement when the shaft encounters increased resistance to rotation comprising an actuating element mounted on said shaft and having a limited rotation with respect thereto, and cam means acting when the shaft encounters resistance and the actuating means are rotating with respect to said shaft to force the engageable friction face elements into engagement.

6. A clamping device comprising two relatively adjustable members and means for effecting relative adjustment of said members and holding them in adjusted position comprising a rotatable shaft for adjusting said members, a first friction face element rotatable with said shaft and held against axial movement thereon, a second friction face element held against rotation and axial movement and engageable with said first friction element for holding the shaft against rotation, a third friction face element rotatable with said shaft, nonrotatable with respect thereto and axially movable thereon, a fourth friction face element held against rotation and axial movement and engageable with said third friction face element for holding the shaft against rotation, helical spring means coaxial with said shaft tending to separate said engageable friction face elements, and actuating means for rotating said shaft when the friction face elements are not engaged and forcing the engageable friction face elements into engagement when the shaft encounters increased resistance to rotation comprising an actuating element mounted on said shaft and having a limited rotation with respect thereto, and cam means acting when the shaft encounters resistance and the actuating means are rotating with respect to said shaft to force the engageable friction face elements into engagement, said shaft having a tubular portion in which said spring means are seated.

7. A clamping device comprising two relatively adjustable members and means for effecting relative adjustment of said members and holding them in adjusted position comprising a rotatable shaft for adjusting said members, a first friction face element rotatable with said shaft and held against axial movement thereon, a second friction face element held against rotation and axial movement and engageable with said first friction element for holding the shaft against rotation, a third friction face element rotatable with said shaft, nonrotatable with respect thereto and axially movable thereon, a fourth friction face element held against rotation and axial movement and engageable with said third friction face element for holding the shaft against rotation, helical spring means coaxial with said shaft tending to separate said engageable friction face elements, actuating means for rotating said shaft when the friction face elements are not engaged and forcing the engageable friction face elements

into engagement when the shaft encounters increased resistance to rotation comprising an actuating element mounted on said shaft having a limited rotation with respect thereto and held against axial movement thereon, cam means acting between said actuating element and one of said axially movable friction face elements when the shaft encounters resistance and the actuating means are rotating with respect to said shaft to force the engageable friction face elements into engagement, said shaft having a tubular portion in which said spring means are seated and said tubular portion having a lateral opening and force-transmitting means acting between said spring means and said axially movable element and extending through said lateral opening.

8. A clamping device comprising two relatively adjustable members and means for effecting relative adjustment of said members and holding them in adjusted position comprising a rotatable shaft for adjusting said members, a first friction face element rotatable with said shaft and held against axial movement thereon, a second friction face element held against rotation and axial movement and engageable with said first friction element for holding the shaft against rotation, a third friction face element rotatable with said shaft, nonrotatable with respect thereto and axially movable thereon, a fourth friction face element held against rotation and axial movement and engageable with said third friction face element for holding the shaft against rotation, helical spring means coaxial with said shaft tending to separate said engageable friction face elements, actuating means for rotating said shaft when the friction face elements are not engaged and forcing the engageable friction face elements into engagement when the shaft encounters increased resistance to rotation comprising an actuating element mounted on said shaft having a limited rotation with respect thereto and held against axial movement thereon, cam means acting between said actuating element and one of said axially movable friction face elements when the shaft encounters resistance and the actuating means are rotating with respect to said shaft to force the engageable friction face elements into engagement, said shaft having a tubular portion in which said spring means are seated and said tubular portion having a lateral opening and force-transmitting means acting between said spring means and said axially movable element and extending through said lateral opening, said force-transmitting means being adjustable to vary the tension of the spring means.
